UNITED STATES PATENT OFFICE.

FRED J. HOYT, OF CHICAGO, ILLINOIS.

RAILWAY-SWITCH MECHANISM.

SPECIFICATION forming part of Letters Patent No. 431,357, dated July 1, 1890.

Application filed April 17, 1890. Serial No. 348,345. (No model.)

To all whom it may concern.

Be it known that I, FRED J. HOYT, a citizen of the United States, residing at Chicago, in the county of Cook and State of Illinois, have 5 invented certain new and useful Improvements in Railway-Switch Mechanism; and I do hereby declare the following to be a full, clear, and exact description of the invention, such as will enable others skilled in the art to 10 which it appertains to make and use the same.

My invention relates to railway-switch mechanism; and its objects are to dispense with the use of a frog, and to present at all times a continuous and unbroken rail for the 15 main and side tracks, making a solid main and a solid side track.

In the well-known system of rails in which a frog is employed—for instance, what is termed a "No. 9 angle"—the distance from 20 the heel of switch-point to the point of frog is usually sixty feet, and the movable switch-rails from that point thirty feet in length. Therefore from the point where the switch-rails begin to diverge from the main track to 25 where they cross the main track is about ninety feet. Now I propose to place a switch-stand in such case at the center of this curve, or, in the instance mentioned, at forty-five feet from that point each way from the stand 30 where the switch-rails begin to diverge from the main track. The rails divided at the stand are to be movable in opposite directions from this point, and for this purpose and to preserve the gage the rails are securely 35 tied.

My invention is illustrated in the accompanying drawings, in which—

Figure 1 is a plan of track and switch-stand with the switch in the main track, and Fig. 2 40 a similar view of the siding; Figs. 3 and 4, details of the switch mechanism.

Referring to the drawings, A A' are the main rails and B the switch-rail. h are the tie-rods for securing these rails together, and

g are stationary fillings secured to a tie for 45 the purpose of closing completely the space between the ends of the rail-sections when they are moved from the main track to siding.

A² is a switch-stand, composed of a broken cog-wheel a, provided on the open part with 50 arms c for operating the same, and which gears with a cog b, mounted on a shaft d. The shaft d carries at its ends cogs c', which engage with wider cogs f, which in turn engage with rack-bars g' on both sides of the 55 stand, and solidly secured to the movable rails by clips g².

The operation of the apparatus is as follows: Let the track be set as in Fig. 1 on main track. If desired to run in on siding, the 60 wheel a² is unlocked and turned by the arms c a given distance, whereby the connecting-gear is rotated, which in turn moves the rack-bars g each in opposite directions and an equal distance, the rail-sections on both sides 65 of the stand also being simultaneously moved in opposite directions until the rails engage with the stationary filling g, forming the continuous side track, as shown in Fig. 2. It will be seen that this gear mechanism is so 70 connected with the main and side rails that when one rack-bar is moved in one direction the other rack-bar will be moved in the opposite direction to throw the rails, as shown in the drawings.

What I claim is—

The combination, with a switch mechanism, of two sections of movable tied rails, arranged on opposite sides of said switch; and stationary fillings for closing the space between the 80 ends of the rail-sections, substantially as described.

In testimony whereof I affix my signature in presence of two witnesses.

FRED J. HOYT.
